JULIUS SHELDON, OF NEW YORK, N. Y.

Letters Patent No. 89,601, dated May 4, 1869.

IMPROVEMENT IN HAT-BLOCKING MACHINES.

The Schedule referred to in these Letters Patent and making part of the same.

To all whom it may concern:

Be it known that I, JULIUS SHELDON, of the city, county, and State of New York, have invented a new and useful Improvement in Hat-Blocking Machines; and I do hereby declare that the following is a clear and full description thereof, reference being had to the annexed drawings, which show, in various positions, that part of a blocking-machine which performs the blocking of the crown of the hat, with my improvement attached thereto.

A great difficulty heretofore existed in those blocking-machines which stretch and form the crown of the hat, by expandable bars, on account of the uneven stretch that the periphery of the crown receives by those bars, as the felt does not seem to stretch between the bars, but draws into the spaces, thus leaving the edge of the crown corrugated, as indicated by the red line in Figure 3, which figure represents a plan view of the ends of those expandable bars.

My improvement is intended to obviate this difficulty; and

It consists in an elastic India-rubber cap, *a*, placed over the ends of the expandable bars *b*, as shown in Figure 1, which represents a vertical section of all

those parts of the machine which perform the stretching of the crown, with the rubber cap *a* placed over the ends of the bars *b*.

This cap is made to fit over the ends of said bars, when contracted, forming a continuous circumference. It is made thick enough all around its cylindrical part to prevent the felt from drawing in between the bars, when the hat-body is placed over it, as shown in fig. 1, and the bars, rubber cap *a*, and felt expanded, as shown in Figure 2, the felt being indicated by red lines in both these figures.

Figure 4 being a plan view of the ends of said bars, with the rubber cap on, expanded, shows, in red line, the shape of the crown of the hat, when said cap is applied.

What I claim as my invention, and desire to secure by Letters Patent, is—

In combination with a hat-stretching or blocking machine, the continuous rubber cap *a*, applied substantially as and for the purpose set forth.

JULIUS SHELDON.
